UNITED STATES PATENT OFFICE.

JOHN J. BOCKEE, JR., OF NEW YORK, N. Y.

DESIGN FOR GROCERS' CAN .

Specification forming part of Design No. 5,276, dated September 26, 1871.

To all whom it may concern:

Be it known that I, JOHN J. BOCKEE, Jr., of New York city, in the county of New York and State of New York, have invented a Design for Grocers' Can.

The nature of my design is fully represented in the accompanying drawing, to which reference is made.

The drawing represents a grocer's can, generally used for receiving the retail or sample supply of tea, coffee, &c. The sides are tapered inwardly from the top to bottom, and rest upon a pedestal of the shape shown. The cover being clearly seen in the drawing no special description is given, the characteristic feature of the de-

sign being an inverted frustum of a cone resting upon a pedestal, substantially such as shown, although the can in horizontal section may be of any known and desired geometrical figure.

What I claim as my invention is—

A design for a grocer's can, of the shape and ornamentation substantially such as shown and described.

Witness my hand this 2d day of September, A. D. 1871.

JOHN J. BOCKEE.
